WEB REGISTERING DEVICE

Edward F. Cornock, Springfield, Mass., assignor
to Package Machinery Company, Springfield,
Mass., a corporation of Massachusetts

Application April 28, 1936, Serial No. 76,734

7 Claims. (Cl. 271—2.6)

The present invention relates to improvements on web registering devices of the general type in which adjustments in the longitudinal position of a web are periodically made in accordance with the response of a detecting device such as a photo-electric cell, electrical contacts made through perforations or specially treated areas of the web, or suction devices acting through perforations in the web. One such device is shown in the prior patent to Smith & Cornock, 2,035,201, March 24, 1936, to which reference will be made herein for a description of parts of the apparatus which do not in themselves form a part of the present improvement. In the operation of such prior devices it has been found that on account of the difficulty of securing accurate setting of the normal forward travel given to the web, corrections were necessary with undesirable frequency. Particularly in connection with devices employing a continuously traveling web as distinct from devices in which the web has an intermittent forward movement, the forward travel given at each cycle of the machine operation has previously been adjustable only by changing the driving gears or by means of a friction or belt drive. The first of these adjustment means has the disadvantage of being variable only in steps, so that unless the length of web to be fed was exactly proportional to the gearing available the forward travel of the web would not be correct. The second has the objections of bulk and lack of positiveness.

In accordance with the present invention the forward motion of the web is derived from three sources. The first of these is a gear drive, preferably fitted with change gears so that accommodation can readily be made for different sizes of sheet. The second is a ratchet and pawl drive provided with an adjustable stroke and operative on every cycle irrespective of whether correction is required or not. This drive serves to bring the rough adjustment given by the change gears to the exact constant feed desired. It can be changed by very small amounts if desired, and may be adjusted to maintain the desired feed as atmospheric conditions change the lengths between indicia on the web. The third feed is a ratchet and pawl feed controlled by the indicia and operative to introduce a correction into the feed in the manner described in the prior patent referred to. The first and third feeds are substantially the same in their details as in the prior patent, and will be described in somewhat less detail for that reason. The invention will now be

described with reference to the accompanying drawings, in which

Fig. 1 is a side elevation of a paper feeding mechanism embodying the present invention;

Fig. 2 is a detail, looking from the left in Fig. 1, of the intermittently acting portions of the paper feeding mechanisms, other parts of the apparatus being removed for the sake of clearness;

Fig. 3 is a detail of certain parts shown in Fig. 1;

Fig. 4 is a longitudinal section through the differential gear;

Fig. 5 is a detail section on line 5—5 of Fig. 2; and

Fig. 6 is a detail section on a larger scale taken on line 6—6 of Fig. 2.

The present device is adapted to operate upon a web 20 of paper or other material, this being supplied from a reel 21 journaled upon brackets 22 which extend from the main frame 23. After leaving its reel the web 20 passes over the usual slack take-up roll 24 mounted for swinging movement upon arms 25 pivoted to the frame at 26 and urged in a counterclockwise direction as viewed in Fig. 1 by any suitable spring mechanism. The web then passes guide rolls 29 that position it for the scanning operation of the photo-electric cell or electric eye contained within a housing 30 and cooperating with a light source 31.

The web then passes between upper and lower feed rolls 40 and 41 respectively. The two rolls are geared together by pinions (not shown), the drive being through the lower roll as will be explained. Situated beyond the feed rolls is a suitable knife mechanism fully described in the patent referred to. Finally, the severed sheet is seized between feed belts 47 and 48 which may form a part of a sheet forwarding mechanism.

It will be convenient before taking up the web controlling mechanism to consider the driving mechanism for the feed rolls, it being through this driving mechanism that control of the registration of the web is accomplished. At one end the shaft 49 (Fig. 4) which bears the lower feed roll 41 is extended through the frame, and at a distance from the outer side of the frame has a reduced portion 50 on which is keyed a pinion 51 having a hub portion journaled in an end plate 52 secured to a housing 53 by dowels 54 and by studs 55. At its inner side this housing has a hub portion 56 journaled upon a sleeve 57 which in turn is journaled upon bushings 58 on the shaft 49. A gear 59 is keyed to the sleeve 57 and is rotated at constant speed by mechanism 55

to be described, turning the sleeve at the same constant rate. The outer end of the sleeve is formed with a pinion 61 meshing with a series of differential pinions 62 freely mounted upon the 5 studs 55. A second series of differential pinions 63 are formed integral with those of the first series, and are of somewhat larger size. These latter pinions mesh with the pinion 51 on the end of shaft 49. It will be seen that if the housing 53 is held stationary the gear 59 will, through the pinions 61, 62, 63, and 51, cause the shaft 49 to turn in the same direction and at a constant relative speed dependent upon the number of teeth on the several gears. If the housing is given 10 a bodily rotation the difference in the sizes of the pinions 62 and 63 will cause a relative advance or retardation of the shaft 49 depending upon the direction in which the housing is moved. In the present case the housing is rotated in one 15 direction only, the feed rolls being set to feed a length of web over or preferably under the correct length and the housing being rotated periodically in a single direction with a frequency dependent upon the degree of correction required.

25 Rotation of the housing for corrective purposes is obtained by a ratchet and pawl mechanism receiving its power from the main drive and controlled in its operation by the photo-electric cell which scans the web. Projecting from the machine frame is a non-rotating stud 70 which may be formed from the end of one of the tie bars which hold the frame assembled. A pawl 71 (Fig. 3) is pivoted at 72 to an arm 73 pinned to the stud so that it does not rotate. A spring 74 30 presses on the pawl to hold it against a wide ratchet 75 which is free on the shaft and has fixed to it a gear 76 in mesh with a gear 77 on the housing 53. The pawl 71 serves as a hold-back to prevent movement of the ratchet, and 35 consequently of the housing, in a backward direction.

To the rear of the ratchet an arm 78 (Fig. 5) is freely movable on the stud. One end of this arm is provided with an arcuate slot 79 in which 40 an adjustable pivot 80 is clamped by a nut 81 (Fig. 2). A link 82 joins this pivot with a crank pin 83 carried by a crank 84 upon the end of a rotating shaft 86. A sprocket 87 (Fig. 1) on this shaft is connected by a chain 88 with a 45 sprocket 89 on a drive shaft 90, which may conveniently be a part of the wrapping machine or other mechanism to which the paper feed is applied, so that the shaft 86 is driven continuously at a constant rate. The other end of the arm 50 55 78 is provided with a pivot 91 for a pawl 92 held against the ratchet 75 by a spring 93 and having a tail 94 by which the pawl may be held out of contact with the ratchet.

Situated still further to the rear on the stud 70 60 is a member 95 (Figs. 2 and 6) free on the stud and constantly urged in an anti-clockwise direction (as viewed in Figs. 5 and 6) by a spring 96 coupled between arm 97 on the member 95 and a clip 98 (Fig. 1) on the frame. A second arm 99 65 on the member 95 bears an abutment 100 which, when the spring 96 is left free to act, rests constantly against the pawl tail 94 and keeps the pawl out of contact with its ratchet. A third arm 101 is recessed to receive a sliding dog 102 70 pressed outwardly by a spring. This dog is adapted for engagement with a plate 105 carried on a bell crank 106 pivoted at 107 to the end of an arm 108 fixed against rotation on the stud 70. On the other end of the bell crank is an ad- 75 justable abutment in the form of a screw 109

held in place by a lock nut 110. This screw is positioned so as to be contacted with by a finger 111 projecting from the armature 112 of a standard relay or contact-closing type of electromagnet 113 which is in the circuit controlled by the photo-electric cell. The bell crank 106 is preferably limited in its angular motion by a fixed abutment 114 formed on the arm 108, and by a screw 115 threaded into a lug 116 on the arm and held in place by a lock nut 117. 10

Whenever a current is established in the electromagnet by the photo-electric cell, as is described in said prior patent, the finger 111 will act on the bell crank to swing the plate 105 into its dotted line position in the path of the dog 102 15 as described in said prior patent. The closure of the circuit through the magnet is not critical in its timing, since this circuit is arranged to remain closed for a considerable part of the cycle. Provided that the circuit through the magnet is 20 closed during the inactive or clockwise rotation of the pawl arm and remains closed until the pawl starts its active or counterclockwise movement the action will be the same. In any case the sole direct function of the magnet is to tilt the plate 25 into the path of the dog 102, an operation requiring little expenditure of power as the bell crank may be made nearly evenly balanced. If the dog has not by that time passed the plate in its inactive stroke it is permitted by its spring 30 to ride over it, and when the pawl carrier starts its counterclockwise motion the dog will be caught by the edge of the plate and prevented from further motion. It will be understood that except when the plate is shifted into this position the 35 spring 96 will keep the abutment 100 against the tail 94 of the pawl and the members 78 and 95 will move as a unit with the pawl held out of engagement with the ratchet. When the plate holds the member 95 against movement, however, 40 the abutment 100 can no longer restrain the pawl; and in that case the ratchet is engaged by the pawl and is rotated to cause a corresponding rotation of the housing 53 and therefore a correction in the angular position of the feed rolls. 45 The correction applied is predetermined in amount and is always in a single direction, the amount of correction given to the rolls being governed by the position of pin 80 in the curved slot 79. For a given setting of the pin 80 the 50 correction is constant in amount, and will vary in the frequency of its application as may be required to keep the web in register. One advantage of the present invention, as will be more fully explained later, is that the normal feed 55 of the web can be brought more nearly to that required for perfect registry than has been possible with prior constructions. The more accurately the paper is printed, and the less irregularity there is in the effects of shrinkage or expansion at 60 different points in its length, the smaller the amount of correction that needs to be made. The present apparatus can be adjusted so that the feed at each cycle is as close to normal as the variations in the web will permit, and the amount 65 of the correction can be made smaller to accommodate this more accurate feed. This results in more accurate and closer regulation than has heretofore been possible.

In order to vary the amount of rotation given 70 to the web feed rolls during each cycle, and thereby to control the length of sheet cut, a change speed gearing is provided for driving the lower feed roll 41. It will be recalled that the drive for this roll was obtained from a gear 59 75

acting through the differential gearing described in connection with the feed correcting mechanism. This gear meshes with a gear 145 rotatable on the end of an arm 146 adjustably held to the machine frame at 147. A gear 148 is fixed to gear 145 and meshes with a gear 149 on a driving shaft 150 which receives a constant rotation from the machine to which the sheet feed is to be applied. By changing these gears any desired approximate rate of web feed can be obtained.

In the present invention mechanism is provided for supplementing the constant feed given by the change gears by an adjustable feed which can be varied to give any desired degree of accuracy. The change gears can of course be adjusted only by definite increments, and it is necessarily a somewhat slow operation to remove the gears and substitute others in order to obtain the feed desired. The change gear method of adjustment is desirable in order to obtain sheets of a considerable length, since an oscillatory feed like a ratchet and pawl is limited in the amount of motion that can be given by the feed rolls at any stroke unless the drive is geared up and the effective adjustment of the mechanism thereby made so coarse as to be practically equivalent to the coarse adjustment obtainable through the change gear mechanism. By the present invention, however, the ratchet and pawl mechanism is called upon to produce only a small motion of the feed rolls at each cycle of the machine's operation, and thus a variation in the stroke given to the pawl will produce a fine variation in the rotation of the feed rolls. The fineness of this adjustment is not impaired in any way by the length of the sheet which is to be fed. All major shifts in the length of the sheet are taken care of by the change gear mechanism, and only a constant range of adjustment is taken care of by the adjustable pawl and ratchet mechanism to be described. As an example, if the length of sheet is to be 8 1/4 inches the change gear mechanism will be set to produce about 8 inches of the feed with only the remaining quarter (minus a sufficient amount to give a constant necessity for periodic unidirectional correction) supplied by the adjustable ratchet and pawl mechanism. The details of this adjustable mechanism will now be described.

Carried upon the stationary shaft 70 just to the rear of the member 73 is a bell crank 200 having a bent arm 201 (Figs. 2 and 3) having a pawl 202 pivoted to it at 203 and pressed by a spring 204 against the wide ratchet 75 with which the corrective pawl 92 also contacts. A pivot 205 on the bell crank 200 is joined by a link 206 with a pivot 207 adjustably secured as by a nut 208 in a slot 209 formed in a crank member 210. This member is pinned at 211 to the pivot 83 which is also pinned at 212 to the crank member 84. The effect of this construction is to cause the crank members 210 and 84 to move as a unit in the manner of an offset crank shaft. The pivots 83, to which the link 82 is coupled, and 207, to which the link 206 is coupled, are arranged substantially 180° from each other so that one of the links is moving up while the other is moving down. The pawls 92 and 202 thus act on the ratchet alternately so that the operation of one is not masked by the operation of the other. Any desired angular motion of the pawl 202, from zero to the maximum permitted by the length of the slot 209, may be obtained by shifting the movable pivot 207. It

will be apparent from a comparison of the sizes of the gears 76 and 77 that the feed rolls will be moved a lesser angular distance than the angular motion given to the pawl 202. This permits a very accurate adjustment of the constant feed given at each cycle to the feed rolls, the smallest adjustment possible being much smaller than the pitch distance between successive teeth on the ratchet 75.

The apparatus has been described in some detail in order to make the construction and operation of the preferred form of the invention readily understood. The arrangement and construction of the several parts may, however, be varied within wide limits without departing from the scope of the invention as defined in the accompanying claims. It will also be apparent that the invention may be applied to an intermittent rather than a continuous type of paper feed by imposing an intermittent drive upon the gear 59 through the change gear mechanism. In either case the same advantage will be retained of being able to adjust the constant feed given at each cycle within very narrow limits, so that the frequency of the correction and its magnitude may both be cut down below what was possible with prior devices intended for the same general purpose.

I claim:

1. A web registering device comprising web feed rolls, means for imparting a cyclically constant advance motion to the feed rolls, adjustable means for changing by a constant amount in each cycle the advancing motion of the feed rolls given by the first means, and indicia controlled means operative to introduce a corrective variation into the advance of the feed rolls when required by the condition of register of the web.

2. A web registering device comprising web feed rolls, means for imparting a cyclically constant advance motion to the feed rolls, adjustable means for imparting to the feed rolls at each cycle a further constant advance, and indicia controlled means operative to impart a corrective further advance motion to the feed rolls when required by the condition of register of the web.

3. A web registering device comprising web feed rolls, a three element differential gear, one element of which is connected to the feed rolls, means for imparting to a second element of the differential gear a cyclically constant advance motion, adjustable means for imparting at each cycle a constant motion to a third element of the differential gear, and indicia controlled means operative to impart a corrective motion to said third element when required by the condition of register of the web.

4. A web registering device comprising web feed rolls, a three element gear, one element of which is connected to the feed rolls, means for imparting to a second element of the differential gear a cyclically constant advance motion, adjustable intermittently acting means for imparting at each cycle a constant motion to a third element of the differential gear, and indicia controlled means operable during the periods of inaction of said intermittently acting means to impart a corrective motion to said third element when required by the condition of register of the web.

5. A web registering device comprising web feed rolls, a three element gear, one element of which is connected to the feed rolls, means for imparting to a second element of the differential

gear a cyclically constant advance motion, means including a ratchet and variable throw pawl for imparting at each cycle a constant motion to a third element of the differential gear, and indicia controlled means operative to impart a corrective motion to said third element when required by the condition of register of the web.

6. A web registering device comprising web feed rolls, a three element differential gear, one element of which is connected to the feed rolls, means for imparting to a second element of the differential gear a cyclically constant advance motion, ratchet means geared to a third element of the differential gear, a pair of pawls engageable with said ratchet means, means for oscillating said pawls alternately in their ratchet forwarding directions, means for adjusting the oscillatory motion of one of said pawls, and indicia

controlled means for controlling the engagement of the other of said pawls with the ratchet means.

7. A web registering device comprising web feed rolls, a three element differential gear, one element of which is connected to the feed rolls, means for imparting to a second element of the differential gear a cyclically constant advance motion, ratchet means geared to a third element of the differential gear, a pair of pawls engageable with said ratchet means, means for oscillating said pawls alternately in their ratchet forwarding directions, means for adjusting the oscillatory motion of the pawls independently of each other, and indicia controlled means for controlling the engagement of one of said pawls with the ratchet means. 10 15

EDWARD F. CORNOCK.
